UNITED STATES PATENT OFFICE

110,646

DESIGN FOR A TRAFFIC SIGNAL

Raymond Petrochko, Olyphant, Pa.

Application April 27, 1938, Serial No. 76,770

Term of patent 14 years

To all whom it may concern:

Be it known that I, Raymond Petrochko, a citizen of the United States, residing at Olyphant, in the county of Lackawanna and State of Pennsylvania, have invented a new, original, and ornamental Design for a Traffic Signal, of which the following is a specification, reference being had to the accompanying drawing, forming part thereof.

Figure 1 is an elevational view of a traffic signal, showing my new design.

Figure 2 is a top plan view thereof.

The traffic signal has four sides, each presenting substantially the same appearance.

I claim:

The ornamental design for a traffic signal, as shown and described.

RAYMOND PETROCHKO.
